COUPLER

Willard F. Richards, Depew, N. Y., assignor to
The Gould Coupler Company, New York, N. Y.,
a corporation of Maryland

Application March 22, 1929, Serial No. 349,131

12 Claims. (Cl. 213—128)

The invention relates to couplers and, more particularly, to automatic couplers for use on railway rolling stock.

The principal object of my invention, generally considered, is to provide a coupler with a vertically movable lock adapted for actuation from either above or below, which upon upward movement engages a knuckle opener preferably mounted on an angularly disposed pivot pin so that the tail engaging portion thereof is rearward of the lock actuated portion, said pivot pin being retained in the head in a novel manner and means being provided for interlocking the lifter and lock without the use of auxiliary members while providing for secure connection therebetween and ready disconnection when desired.

Another object of my invention is to provide an automatic coupler in which the knuckle opener thereof is mounted on a headless pivot pin retained by a cotter inserted from the inside of the coupler head to the outer side of the horn so that it can be easily applied or detached therefrom.

A further object of my invention is to provide an automatic coupler with a vertically movable lock and a lifter therefor passing through an opening in the top wall of the head and formed with outstanding integral pintles on its lower end, said pintles being adapted to pass through slots in the top of the lock, when the lifter and lock are disposed at an abnormal angle with respect to one another, said slots being so disposed that upon straightening out the relation between the lifter and lock, said lock is securely held for operation thereby and the pintles are received in corresponding bearing portions in the lock.

A still further object of my invention is to provide an automatic coupler with a vertically movable one-piece lock, said lock being formed with an extension on the bottom thereof for guiding purposes, a portion of said extension providing a shoulder adapted to engage a ledge on the head for lock-setting purposes, a portion of said extension being tapered and fitting in a corresponding pocket for holding the lock from tilting forward into the throat of the head when coupling.

An additional object of my invention is to provide an automatic coupler with a pivoted crank lever for operating the lock, which lever is received in a recess in the side of the head to protect it from injury.

Other objects and advantages of the invention relating to the particular arrangement and construction of the various parts will become apparent as the description proceeds.

Referring to the drawings illustrating my in-

vention, the scope whereof is defined by the appended claims,

Figure 1 is a partial plan and partial horizontal sectional view on the line 1—1 of Figure 2 looking in the direction of the arrows and illustrating one embodiment of my invention.

Figure 2 is a vertical longitudinal sectional view on the line 2—2 of Figure 1 looking in the direction of the arrows.

Figure 3 is a partial side elevational and partial longitudinal vertical sectional view on the line 3—3 of Figure 1 looking in the direction of the arrows.

Figure 4 is a transverse sectional view on the line 4—4 of Figure 1 looking in the direction of the arrows.

Figure 5 is a fragmentary vertical longitudinal sectional view corresponding to Figure 2 but showing a portion of the lock in section, and said lock and its lock lifter angled with respect to one another to abnormal positions to show how said parts are connected and disconnected.

Figure 6 is a transverse sectional view corresponding to Figure 4 but showing another embodiment of my invention.

Figure 7 is a fragmentary longitudinal sectional view corresponding to Figure 2 but illustrating the embodiment shown in Figure 6 with the lock in lock-set position.

Figure 8 is a fragmentary plan of the knuckle side of the head and associated parts with the knuckle removed and further illustrating the embodiment of Figures 6 and 7.

Figures 9 and 10 are sectional views corresponding respectively to Figures 2 and 4 but showing another embodiment of my invention.

Referring to the drawings in detail, like parts being designated by like reference characters, and first considering the embodiment of my invention illustrated in Figures 1 to 5 inclusive, there is shown an automatic coupler 1 comprising a head 2 and a knuckle 3. As is customary, a portion of the knuckle is apertured and fits between lugs 4 on the head formed with apertures registering with the aperture 5 in the knuckle and receiving a connecting pivot pin 6. Said pin may be held in place in any desired manner and in the present instance is shown with a head 7 at its upper end and a cotter 8 passing through the lower end thereof for preventing undesired removal or loss.

The head 2 is hollow to provide a pocket 9 for receiving the tail 10 of the knuckle 3, and a lock receiving pocket or compartment 11 in which fits a vertically movable lock 12, which in the

present embodiment is formed as a single piece or block provided with a depending portion 13 passing through a corresponding aperture 14 in the lower wall 15 of the head for guiding purposes. The extension 13 is preferably notched at 16 to provide a shoulder 17 adapted to engage the ledge 18 on the lower wall 15 of the head to hold the lock in lock-set position. A portion of the extension 13 is tapered downwardly as indicated at 19 and normally received in a correspondingly tapered pocket 29 in the lower wall of the head to provide a lock holder and prevent said lock from tilting forward through the throat of the head when coupling. The lock is so formed with relation to the base of the compartment 11 and the size of the throat or mouth of the head 2 that it is possible to insert the lock through the mouth of the head into position.

The top of the lock 12 is formed with a bearing pocket 22 adapted to receive the lower end of an associated lock lifter 23 and outstanding trunnions or integral pintles 24 thereon. Said pintles are preferably flattened, as illustrated particularly in Figure 5, and access is had to the pocket 22 in the lock through slots 25 when the lock and lifter are angled with respect to one another to an abnormal position, as illustrated particularly in Figure 5. It will be clear that upon straightening out the relation between the lock and lifter to the position illustrated in Figure 2, the pintles 24 will underlie the top wall 26 of the lock so that said lifter is securely interlocked with respect to said lock, while at the same time provision is made for ready disengagement or engagement between the parts. The lock lifter 23 preferably passes through an aperture 27 in the top wall 28 of the head or horn 29 thereon and is widened and apertured at 30, as indicated, so as to provide for connection with operating mechanism, not shown, and to prevent the lifter dropping clear through the aperture 27 into the compartment 11 in the head.

The upper end of the lock 12 is notched, as indicated at 31, to provide a ledge 32 which engages one end 33 of the knuckle opener 34. Said knuckle opener 34 preferably has a hub portion 35 apertured and mounted on a preferably headless pintle or pivot pin 36, which preferably extends at an angle to the longitudinal axis of the head, as shown most clearly in Figure 1 and is inserted into position through the rear wall 37 of the horn 29 of the coupler head 2, and the forward end of which is received in a corresponding pocket 38 adjacent the front wall of the horn 29 where it is stopped against a shoulder 39, as shown most clearly in Figure 1. After said pintle 36 has been applied it is held in place in any desired manner, but preferably by means of a cotter 40 passed from the inside of the head, or mechanism pocket, to the outside, so that the head or loop of the cotter lies in the mechanism pocket of the coupler head and the prongs thereof are extended beyond the outer surface of the head and readily separated to hold said cotter in place, so that the head engages the corresponding end of the pivot pin 36 and securely holds it in position.

The lower or other end of the knuckle opener 34 is extended, as indicated at 41, to the side of the knuckle tail 10, so that upon upward movement of the lock 12, the knuckle opener is finally engaged and rotated to swing the tail of the knuckle outwardly to open or unlocked position. It will be apparent that on account of having the knuckle opener 34 pivoted about a pintle 36 dis-

posed at an angle to the longitudinal axis of the head, the tail engaging portion thereof is rearwardly of the lock-engaging portion, while maintaining the knuckle opener arms in the same plane transverse to the axis of the pivot pin thereof, thereby not only providing a greater leverage for opening the knuckle, but making the force act about an axis approximately radial with respect to the pin 6 about which the knuckle is pivoted, it being clear that the angularity of the pivot pin or pindle 36 makes the axis thereof nearly pass through the axis of said pin 6.

Referring now to the embodiment of my invention illustrated in Figures 6, 7 and 8, an automatic coupler 1^a is illustrated in which the operation is substantially identical with that of the coupler 1 of the first embodiment, except that the vertically movable lock 12^a is operated from below rather than from above. As in the previous embodiment, the coupler head 2^a has a lock receiving compartment 11^a in which moves a lock, preferably one-piece, with an integral extension 13^a received in an aperture 14^a in the lower wall 15^a of the head. Said lock upon vertical movement engages the knuckle opener 34^a which may be identical with that of the previous embodiment and be mounted on an angularly disposed pivot pin 36^a as in the previous embodiment, so that when said knuckle opener is engaged by the lock it swings to move the tail 10^a and the knuckle to open position.

In the present embodiment the extension 13^a of the lock 12^a is pivotally mounted on the upper end of the lock lifter 23^a as by means of a pivot pin 24^a. Said lifter preferably passes between spaced depending portions 42 and 43 of the extension 13^a, said extensions preferably diverging so as to permit a limited amount of longitudinal angling of the lock 12^a, as shown most clearly in Figure 7, so that when moved upward into the head the lower end of the extension 43 may seat upon the lock-set ledge 18^a in the head and hold said lock 12^a in lock-set position from which it is disengaged by the tail of the knuckle swinging therebeneath on closing motion thereof.

The lower end of the lock lifter 23^a is pivotally connected to the bent operating lever 44, preferably between the arms 45 and 46 of the bifurcated portion 47, a pin 48 preferably passing through registering apertures in said portions and the lower end of the lifter 23^a and retained in position by a head 49 at one end and a cotter 50 at the other. The intermediate or hub portion of the lever 44 is preferably mounted between the lugs 51 and 52 depending below a side wall of the head and through which passes a connecting pivot pin 53 preferably headed at one end, as indicated at 54, and retained in place by a cotter 55 at the other end. The upper portion or end 56 of the lever 44 is preferably apertured, as indicated at 57, for connection with side operating means, not shown, and is normally received in a recess 58 formed behind a bulge or outwardly embossed portion 59 on the knuckle side of the head, so that said lever is normally protected from injury. Except as specifically described in connection with the present embodiment the same may correspond substantially with that of the first embodiment.

Referring now to the embodiment of my invention illustrated in Figures 9 and 10, a coupler 1^b is illustrated which is similar to that of the previous embodiments, except that the bottom of the head is formed to accommodate a rocker shaft 60 and connection to the lock to form a bottom operated coupler. Said lock 12^b is preferably

formed with an extension 13^b bifurcated to receive therebetween a lock lifter 23^b, as in the previous embodiment, the bifurcation, however, being longitudinal rather than transverse, so that the portions thereof fairly closely embrace the lock lifter 23^b, at the same time permitting said lock to tilt forwardly so that the lower end of the extension 13^b engages the lock-set ledge 18^b in the lock-set position. In locked position, as illustrated in Figure 9, the lower ends of the extension 13^b engage the operating crank 61 rigidly mounted on the rocker shaft 60 and pivotally connected to the lower end of the lock lifter 23^b by a pivot pin or the like 62. In order to limit downward movement of the crank 61, the head 2^b is provided with a ledge 63 underlying the outer end of the crank 61 and providing a limit stop therefor, so that said crank then provides a firm abutment upon which rests the lower end of the lock extension 13^b.

The rocker shaft 60 may be operated in any desired manner as by means of a transversely extending rod 64 hooked into a head 65 on the shaft 60, said shaft being retained in position by means of a washer 66 on the other end retained thereon by a cotter of the like 67. As in the previous embodiments, upon vertical movement of the lock when the shaft 60 is rotated clockwise, as viewed in Figure 9, said lock engages the knuckle 34^b, which may be mounted as in the previous embodiments, which upon movement engages the tail 10^b of the knuckle 3^b and moves the latter to open position. Except as specifically described in connection with the present embodiment, the same may correspond substantially with that of the first embodiment.

From the foregoing description taken in connection with the accompanying drawings, it will be seen that I have devised an improved automatic coupler which may be operated from above or below and if operated from below either by pulling a lever sideways or rotating a shaft, said coupler having a vertically movable one-piece lock with depending guiding and holding portions, said lock engaging a knuckle opener pivoted on a pin, the axis of which is angularly disposed with respect to the longitudinal center line of the head and which upon movement engages the tail of the knuckle to open the same. I have provided novel means for mounting the knuckle opener pin, for providing a lock-set feature for a one-piece lock and for conveniently interlocking the lock lifter and lock while providing for ready engagement and disengagement.

Although I have illustrated and described certain preferred embodiments of my invention, it will be understood that I do not wish to be limited to the details as modifications may be made without departing from the spirit of my invention and the scope of the appended claims.

Having now described my invention, I claim:

1. In combination, a coupler head with walls defining a mechanism pocket, a knuckle pivoted thereto, a locking block vertically movable in said pocket and guided by said walls, a lock lifter operating in an aperture in the upper wall of said head and having trunnion means with a flattened normally vertical side interlocking with said block, said block having a slot extending diagonally rearward and upward, from a pocket adapted to pivotally receive and normally provide for interlocking of the trunnion means therein, and in width corresponding with the minimum width of the trunnion means, to provide for assembly and disengagement with respect to said

lifter only when the block and lifter are disposed in an abnormal angular relation.

2. In combination, a coupler head, a knuckle pivoted thereto, a vertically movable lock with a bearing pocket from which a slot extends diagonally rearward and upward, a lock lifter with trunnion means flattened in a normally vertical plane so as to pass said slot, when said trunnion means is in a position abnormal with respect to said lock, said lifter being adapted for raising said lock when in normal position with the trunnion means in the pocket.

3. In combination, a coupler head with a mechanism pocket, a knuckle, a lock vertically movable in said pocket, a knuckle opener comprising a bell crank lever with one arm engaged by said lock upon upward movement thereof and the other engaging said knuckle, and means for mounting said knuckle opener in said head comprising a pin with its intermediate portion supporting said knuckle opener and its end portions mounted in said head, that portion of said head receiving one end of said pin being formed with a shoulder limiting longitudinal movement of the pin in one direction, the other end of said pin being received in an apertured portion of said head, said apertured portion being extended axially beyond the normal position of the pin to the outer surface of a wall of the mechanism pocket, and merging at one side with said pocket, and a cotter with a portion disposed in the extension of said aperture beyond said pin, adjacent the plane of emergence with the pocket, for limiting movement of the pin in the other direction and its prongs passing through the wall of the mechanism pocket and bent to locking position on the outer surface thereof, whereby said cotter is insertable and removable from the inside of said pocket.

4. In combination, a coupler head with a mechanism pocket and an upstanding horn, a knuckle, a locking block vertically movable in said pocket, a knuckle opener actuated by said block, and a pivot pin for said opener, one end of said pin being supported in a pocket in the head and the other end in an aperture opening into said mechanism pocket and extending to the outer surface of the horn, and means closing said aperture and normally overlying the end of said pin in said aperture, said means being locked in place at the outer surface of the wall and being insertable and removable from the mechanism pocket.

5. In combination, a coupler head, a swinging knuckle, a vertically movable lock, a knuckle opener actuated by engagement of the upper portion of said lock therewith and provided with arms lying in the same plane transverse to the axis thereof, a pin on which said opener is adapted to pivot, said pin being formed with end portions on opposite sides of said opener supported by said head and extending at an angle to the longitudinal axis of the head, so that the lock engaged part of said opener is forward of the tail engaging portion, a shouldered portion of the head preventing displacement of the pin in one direction by lying adjacent one end of said pin, and removable means normally overlying the other end of said pin for preventing displacement in the other direction.

6. In combination, a coupler head, a vertically movable lock, a substantially parallel sided extension on the bottom of said lock normally passing through a corresponding aperture in the bottom of said head for guiding purposes, said extension being formed with a tapered portion at one side,

and said head having a corresponding pocket in which said tapered portion is supported when the lock is in locked position.

7. In combination, a coupler head, a vertically movable lock, a lock lifter connected thereto so that the greater proportion of the weight of the lock is forward of the connection with the lifter, whereby said lock tends to tilt forward, a ledge on the head adjacent the rear portion of the lock receiving compartment therein, and an extension on said lock formed with a portion tapered at such an acute angle and supported in a corresponding pocket in the head when the lock is in lowermost position so that said lock will then be held from forward tilting, said extension having a portion engaging said ledge for holding the lock in lock-set position.

8. In combination, a coupler head with an aperture in the lower wall thereof, a vertically movable lock adapted to tilt longitudinally of the head into lock-set engagement therewith, an extension on said lock adapted to pass through said aperture, a tapered portion on a side of said extension, said head being provided with a correspondingly formed pocket in which said tapered portion fits for holding the lock from tilting forward into the throat of the head when in locked position.

9. In combination, a coupler head with a tapered pocket in a longitudinal upright wall thereof, a knuckle pivoted thereto, and a vertically movable one-piece lock formed with a tapered depending extension adapted to snugly fit said pocket for holding it in proper position in said head and preventing forward tilting thereof.

10. In an automatic coupler, in combination, a head, a knuckle, a pin connecting said knuckle to said head, a lock vertically movable in said head, the upper portion of said lock having a pocket

opening diagonally upward and rearward, a lock lifter operating in an aperture in the upper wall of said head, the lower portion of said lifter having trunnions normally interlocked in said pocket and removable therefrom only upon tilting to place the lock and lifter in an abnormal relative position, and a knuckle opener pivotally mounted in the head and engaged by the lock upon upward movement to actuate the knuckle.

11. In an automatic coupler, in combination, a head, a knuckle, a pin connecting said knuckle to said head, a lock vertically movable in said head, said lock having a depending guiding extension normally received in a corresponding aperture in the bottom of the head and formed at a side with a tapered portion adapted to fit in a correspondingly formed pocket in the head for holding the lock in locked position and preventing it from tilting forward into the throat of the head, a lock lifter, means connecting said lifter and lock, and a knuckle opener pivotally mounted in the head and engaged by the lock upon upward movement thereof to actuate the knuckle.

12. In an automatic coupler, in combination, a head, a knuckle, a pin connecting said knuckle to said head, a lock adapted to move up and down in said head, the upper portion of said lock having a pocket connecting with a passage opening diagonally upward and rearward, a lock lifter operating in said head and having trunnions formed on the lower portion thereof adapted to pass through said passage only when lock and lifter are disposed in an abnormal angular relation to said pocket to interlock with the lock, and a knuckle opener pivotally mounted in the head and adapted for engagement by the lock to actuate the knuckle.

WILLARD F. RICHARDS.
